UNITED STATES PATENT OFFICE.

ROY HEWITT, OF STERLING, ILLINOIS.

BALE-TIE MACHINE.

Application filed January 10, 1924. Serial No. 685,480.

My invention relates to bale-tie machines, and has reference more specially to a machine of that type which is set forth in Letters Patent of the United States No. 5 885,916, issued to William D. Ferris, April 28th, 1908. The improvement has to do with certain parts of the mechanism in said machine, which are more particularly disclosed in Figures 23 to 28, inclusive, of the drawings in said patent, and are described under the heading—"The device for forming the twisted eye *a* at the end of the tie", on page 9 of the specification. This device includes a bending-pin (283) for forming a loop in 10 the end of the tie wire, and in the operation of bending the wire, and returning the parts to their original positions, it frequently happens that the wire is accidentally bent 15 near the loop therein, so as to interfere with the proper bundling of the ties for shipment. This is apparently caused by the bending pin in its return movement, and the chief purpose of the present invention is to replace the wires in their former straight 20 line, in case they have been bent out of shape. The mechanism for doing this consists of an attachment for the eye-forming devices, such as are shown in said former patent. Certain parts of the original machine 25 have been included in the present drawings, to better illustrate the invention, and show the relation of the parts to those of the former machine.

In the drawings:—

Fig. 1 is a front elevation, showing parts 35 of said former machine, as disclosed in Fig. 23 of said patent, with the present invention applied thereto.

Fig. 2 is a plan view of the invention, 40 detached.

Fig. 3 is a face view thereof, looking at the end of the jaw C.

The parts of the former machine are indicated in the drawing in capital letters, 45 said parts including a support or base-block A, carrying the lower stationary vise B, and a rockably mounted jaw C, in which is mounted a clamping die D. The jaw C is pivoted in the base A, as at *a*, and is designed 50 to be rocked upwardly, to release the tie wire, after the eye is formed in the end thereof, by means of mechanism set forth in said former patent, and not specially involved herein. A bearing E is supported 55 in the machine, in which is journaled a shaft F, on the end of which is a twisting mech-

anism G, and operatively mounted on the block A is a bending pin crank H, adapted to form a loop in the end of the wire. During this operation the wire, shown at 11, is 60 looped round the pin G' of the twisting devices, after which said pin is withdrawn and the bending-pin H' returned to its former position, evidently coming in contact with the looped end of the wire and bending 65 the same. The arrangement and timing of the operating devices is such that immediately following the forming of the eye in the end of the wire the jaw C is rocked upwardly, so as to permit the release of the wire. 70 This upward movement of the jaw is made use of in operating the attachment, the parts of which are as follows:—

Secured to the top of the jaw C is a plate 1, upon which is slidably mounted a plate 2, connected by a rod 3 with a bracket 4, supported on the bearing E. The plate 2 is recessed, and provided at one end thereof with a cam face 5, in engagement with the upper end of a lever 6, fulcrumed in a recess 7 in the plate 1, as at *b*. The lower end of said lever is connected with a bar 8, extending transversely of the lower face of the jaw C, and slidably supported at its other end in a hanger 9, depending from the plate 1. Projected downwardly from the bar 8 is a cam-shaped member 10, at one side of the wire 11, when in position in the jaws of the machine. A contractile coiled spring 12 connects the upper end of 80 the lever 6 with a post 13, fixed on the plate 1, the purpose of said spring being to return 85 said lever to its normal position, with the cam member 10 in contact with the wire 11, as shown in Fig. 3.

When the jaw C is in a lowered position the inclined edge 5 is in position to force the upper end of the lever 6 outwardly, moving the bar 8 to carry the cam 10 outwardly, so as not to interfere with the movement 100 of the wire 11. After the twisting operation, as the jaw C is elevated, the distance between the upper end of the lever 6 and the post 4 is shortened sufficiently to permit a return movement of such upper end to the inner end of the recess 7, this movement being impelled by the spring 12. This takes place as the jaw is being raised, and in this movement the cam 10 is brought inwardly 105 into contact with the wire. If such wire has been bent out of a straight line in the direction of the cam 10, the return action 110

of said cam serves to force such wire back into a straight line.

To facilitate the operation of the parts, the rod 3 has a pivotal connection with the plate 2, the operation of the plate 2 being the same as it would be if the jaw C were in a fixed position, and the bracket 4 movable with relation thereto.

The engaging edge of the cam 10 is curved 10 to prevent the same from carrying the wire upwardly in the upward movement of the jaw C and appurtenant parts.

What I claim, and desire to secure by Letters Patent, is:

15 1. In combination with the frame of a bale-tie machine, and a pair of wire-gripping jaws supported therein, one of which is rockably mounted with relation to the other, a wire straightening cam, movable beneath said rockable jaw, transversely thereof, a fixture supported on the frame, in proximity to said last-named jaw, and means connected with said fixture for actuating said wire straightening cam upon said last-named jaw being suitably rocked.

20 2. In combination with the frame of a bale-tie machine, and a pair of wire-gripping jaws supported therein, one of which is rockably mounted with relation to the other, a wire-straightening cam movable beneath said rockable jaw, transversely thereof,

a plate slideable on said jaw, at right angles with said wire straightening cam, a fixture supported on said frame, means connecting said slideable plate with said fixture, and means for imparting the movement of said slideable plate to said straightening cam, to cause the same to operate upon said rockable jaw being suitably actuated.

25 3. In combination with the frame of a bale-tie machine, and a pair of wire-gripping jaws supported therein, one of which jaws is rockably mounted with relation to the other, a fixture on the frame in proximity to said last-named jaw, a wire straightening cam operable beneath said last-named jaw, transversely thereof, a lever fulcrumed at one side of said last-named jaw and operatively connected with said wire straightening cam, a slide-plate mounted on said last-named jaw, having a positive connection with said fixture, and in engagement with said lever to move said wire straightening cam out of operative position upon said rockable jaw being moved toward the fixed jaw, and means for returning said straightening cam to an operative position upon said rockable jaw being moved away from said fixed jaw.

50 55 In testimony whereof I affix my signature.

ROY HEWITT.
